UNITED STATES PATENT OFFICE.

FRANK W. MERRICK, OF BOSTON, MASSACHUSETTS.

PRESSER-LIFTING DEVICE.

Application filed December 28, 1917. Serial No. 209,359.

To all whom it may concern:

Be it known that I, FRANK W. MERRICK, a citizen of the United States, residing at Boston, in the county of Suffolk, State of

5 Massachusetts, have invented a certain new and useful Improvement in Presser-Lifting Devices, of which the following is a specification, reference being had therein to the accompanying drawings.

10 My improved presser-lifting devices are applicable to various kinds of machines, although shown and described herein with reference to their employment in connection with a sewing machine.

15 The said devices are an improvement in presser-lifting devices on the order of those of my prior Letters Patent No. 629,108, granted July 18, 1899, namely: of the class in which a presser-bar having a portion of 20 its length screw-threaded has combined with it a revoluble nut fitting the said screw-threaded portion, and a lifter-device intermittently actuated by a lifting actuator and which by the first portion of its upward 25 movement clamps and locks the nut so as to prevent it from revolving around the screw-threaded portion of the presser-bar, and by the latter portion of such movement operates through the locked nut to raise the 30 presser-bar and presser.

The general object of the invention is to provide presser-lifting devices, applicable to sewing and other machines, which shall be free from disadvantages and drawbacks 35 of devices for the same purpose heretofore in use.

The invention provides devices capable of easy and light action, free from material liability to cause lateral pressure of the 40 presser-bar within its guides or bearings and resulting wear of the presser-bar and guides or bearings.

The invention involves the employment of a compound-lever lifter-device comprising 45 a nut-locking secondary lever-member and a primary lever-member against which the lifting actuator acts to actuate the said secondary lever-member for the purpose of locking the nut from turning, and to raise 50 the presser and associated parts and control the descent thereof. The invention involves also a particular arrangement and relationship of the said lever-members and lifting actuator by which the tendency to lateral 55 pressure and wear is practically eliminated.

The drawings show an embodiment of the invention applied in connection with the presser and presser-bar of a sewing machine.

Fig. 1 is an elevation of certain parts of the said machine, looking at the head-end thereof, showing the said embodiment.

Fig. 2 is a partly sectional view of the parts that are shown in Fig. 1, looking from the right-hand side in Fig. 1.

Figs. 3 to 11, inclusive, are views of detail parts to which reference is made in the course of the following description.

The drawings show the upright 1 and 70 horizontally extending arm 2 of the main fixed part of a sewing machine, the head 3 at the outer end of said arm, the presser-bar 4 fitted for movement vertically in and with relation to the said head, the presser 5 carried by the presser-bar, the presser-depressing spring 4^a acting downwardly upon the top of the presser-bar 4, and the work-support 75 6.

At 7 is the screw-threaded upper portion 80 of the presser-bar, preferably formed with a quadruple thread in order to give a very sharp angle of pitch. At 8 is the nut which is mounted upon this threaded portion of the presser-bar, with its internal thread engaged with the said spiral thread of the presser-bar. The said nut is shown separately in side elevation and plan, respectively, in Figs. 3 and 4.

A carrier-member constituted by an arm 9, shown separately in plan in Fig. 5, is mounted upon the said threaded portion of the presser-bar by means of lugs 9^a, 9^b, Figs. 1 and 2, of said arm which have smooth holes 9^b, Fig. 5, therethrough through 95 which the said portion of the presser-bar passes, one of said lugs being above the nut 8 and arranged to make contact with the top side thereof and the other lug being below the nut and arranged to make contact 100 with the bottom side thereof. This interengagement of the two lugs with the top and bottom of the nut provides for movement of the nut and carrier-member vertically in unison. A contracting spiral spring 105 16 exerts a downward pulling force upon arm 9, and aids gravity in returning the arm to its position in Fig. 1 with its lower lug 9^a resting upon the top end of the stop sleeve 17 carried by the bearing-portion 3^a 110 of the head 3.

The lower portion of the presser-bar 4

works in a guide-hole or bearing made vertically through the lower portion 3^a of the head 3 . The screw-threaded upper portion of the presser-bar fits within a sleeve 9^b connected with and rising from the upper lug 9^a of arm 9 , and is adapted to move vertically in and through the said sleeves. The sleeve 9^b , in turn, is fitted to a guide-bearing in the upper portion 3^b of the head 3 , and is adapted to move vertically in and through said guide-bearing. The sleeve is itself a bearing for the screw-threaded upper portion of the presser-bar, and in addition constitutes an elongated bearing for the arm 9 upon the presser-bar by which tendency of the arm to cramp against the presser-bar so as to interfere with the desired relative vertical movement of these two parts is obviated.

20 In the present embodiment of the invention, the arm 9 is slotted vertically throughout the greater portion of its length as shown in Fig. 5, and within the slot as shown in Fig. 1 is fitted a nut-locking lever 10 , which is mounted upon said arm by means of a pivot 11 located at a point close to the presser-bar. Fig. 6 shows the said lever 10 in side elevation, and Fig. 7 is a plan thereof. Lever 10 is a lever of the first order. Its inner arm has its end concaved to fit the exterior of the nut. The power-arm of said lever extends outward from pivot 11 . Another lever, 12 , shown separately in side elevation in Fig. 8 and in plan in Fig. 9, is mounted upon arm 9 within the slot of the latter by means of a pivot 13 that is located farther away from the presser-bar than the pivot 11 of lever 10 . The lever 12 is a lever of the second order. It extends from its pivot 13 toward the presser-bar, and the outwardly-extending power-arm of lever 10 rests upon the top of lever 12 . Lever 12 rests upon the grooved top of a lifting-actuator constituted by a rocker-arm 14 , Figs. 10 and 11, fixed upon the outer end of a rock-shaft 15 , Figs. 2 and 11, that is mounted in bearings (one of which is shown at 16, Fig. 2) in connection with machine-arm 2 . Fig. 10 is a side elevation of rocker-arm 14 , and Fig. 11 is a plan of the said rocker-arm and the outer end of rock-shaft 15 . The lower portion of the lever 12 fits between the raised side-walls 14^a , 14^b , of rocker-arm 14 while its top extends up between the side-walls of the arm 9 . By means of the two pairs of side-walls the lever 12 is kept from side-wise displacement.

60 As rocker-arm 14 is rocked upwardly from its position in Figs. 1 and 2, its upward pressure, acting through lever 12 against lever 10 , causes the inner arm of lever 10 to engage with the nut 8 , gripping the nut so that the latter is locked effectually from turning upon the threaded portion of the presser-

bar. After lever 10 brings up firmly against nut 8 , the continued upward rocking movement of the rocker-arm has the effect of lifting the presser-bar and presser. The succeeding downward movement of rocker-arm 14 lowers the arm 9 , presser-bar, and presser, until the presser rests upon the top surface of the work, or upon the work-support, or until the arm 9 rests upon the top end of stop-sleeve 17 . In the lowering movement, the combined downward pressure of presser-depressing spring 4^a acting through the nut 8 , arm 9 , lever 10 and lever 12 , and pull of spring 16 , keeps lever 12 firmly pressed against the rocker-arm until the presser rests upon the work or work-support or the arm 9 rests upon the top end of stop-sleeve 17 . Until then the nut is kept locked and the presser-bar and presser under the control of the rocker-arm while the presser-bar and presser are being lowered. As soon as the presser takes bearing upon the top surface of the work or the work-support, or the arm 9 takes bearing upon the top end of the stop-sleeve 17 , the pressure of the inner end of lever 10 against the nut is relaxed, so that the nut is left free to turn, whereupon the nut turns so as to permit arm 9 to adjust itself downward until it touches the top of stop-sleeve 17 , or the presser to adjust itself downward until it bears upon the surface of the work or of the work-support.

The extension of the rocker-arm 14 inward from the rock-shaft 15 toward the presser-bar, the action of the rocker-arm against the under side of lever 12 at points between pivot 13 and the presser-bar, and the action of lever 12 against the under side of lever 10 between said pivot and the presser-bar, enable the lifting pressure to come close to the axis of the presser-bar, without noticeable tendency to produce lateral pressure of the presser-bar within its bearings, or of sleeve 9^b within its bearing at 3^b , such as would occasion undue friction and cramping. Consequently wear of the bar and bearings is obviated.

The levers 12 and 10 constitute a compound lever, by which the effective leverage in clamping the nut is increased, and an easier action, with still further diminution in the lateral pressure of the presser-bar. As will be apparent, the lever 12 (herein a lever of the second order) constitutes the primary lever-member of the compound lever arrangement, the lifting actuator acting thereagainst for the application of power to the compound lever, and the nut-locking lever 10 (herein a lever of the first order) constitutes the secondary lever-member of the compound lever arrangement. The illustrated combination of levers gives the best results in practice.

My invention obviates the disadvantages

of prior constructions of presser-lifting devices.

What is claimed as the invention is:—

1. In presser-lifting devices comprising a presser, a presser-bar having a screw-threaded portion, a revoluble nut fitting said portion, a carrier engaging with said nut for unison vertical movement therewith, and a lifting actuator, the combination therewith, of a compound-lever device mounted in connection with said carrier and comprising a nut-locking secondary lever-member and a primary lever-member respectively pivoted to said carrier the said lifting actuator acting to actuate said secondary lever-member for the purpose of locking the nut from turning, and to raise the presser and associated parts and control the descent thereof.
2. In presser-lifting devices comprising a presser, a presser-bar having a screw-threaded portion, a revoluble nut fitting said portion, a carrier engaging with said nut for unison vertical movement therewith, and an actuating rocker, the combination therewith of a compound-lever device mounted in connection with said carrier and comprising a nut-locking secondary lever-member and a primary lever-member respectively pivoted to said carrier, the said rocker acting

to actuate said secondary lever-member for the purpose of locking the nut from turning, and to raise the presser and associated parts and control the descent thereof.

3. In presser-lifting devices comprising a presser, a presser-bar having a screw-threaded portion, a nut fitting said portion, a carrier engaging with said nut for unison vertical movement therewith, and an actuating rocker-arm swinging vertically between its axis of oscillation and the presser-bar, the combination therewith of a compound lever device mounted in connection with said carrier and comprising a nut-locking secondary lever-member having a power-arm extending away from the presser-bar, and a primary lever-member having an outstanding pivoted connection with said carrier and with which the rocker-arm engages between said pivot and the presser-bar for the purpose of locking the nut from turning, and to raise the presser and associated parts and control the descent thereof.

In testimony whereof I affix my signature in presence of two witnesses.

FRANK W. MERRICK.
